DESIGN.

F. A. MAGEE & S. VAN VORST.

HEATING STOVE AND FURNACE.

No. 16,985.

Patented Nov. 16, 1886.

Fig. 7.

Fig. 2.

UNITED STATES PATENT OFFICE.

FRANK A. MAGEE AND SYLVESTER VAN VORST, OF CHELSEA, ASSIGNEES
TO THE MAGEE FURNACE COMPANY, OF BOSTON, MASSACHUSETTS.

DESIGN FOR A HEATING STOVE AND FURNACE.

SPECIFICATION forming part of Design No. 16,985, dated November 16, 1886.

Application filed September 30, 1886. Serial No. 215,015. Term of patent 14 years.

To all whom it may concern:

Be it known that we, FRANK A. MAGEE and SYLVESTER VAN VORST, both of Chelsea, in the county of Suffolk and State of Massachusetts, 5 citizens of the United States, have invented a new and original Design for Heating Stoves and Furnaces, of which the following is a full, clear, and exact specification.

Our newly-invented design for a heating 10 stove or furnace is illustrated in the accompanying photographs, in which the photograph marked Figure 1 is a view in front elevation, and the photograph marked Fig. 2 is a view in side elevation.

15 A represents the base of the stove or furnace; B, the cylindrical body; C, an extension of the base, which extends laterally from the sides and back of the base and beyond the cylindrical section B, as shown in photograph 20 Fig. 2.

D is a pipe which extends from the rounded projection d, near the top of the cylindrical section B, to the extension C of the base.

E is a pipe extending from the rounded collar or box e, which projects horizontally from the back of the body C, near the top, to the extension B of the base.

F is a box or easing having rounded corners, which extends laterally from the front of the 30 body C near the top, and which is otherwise shaped as represented in photograph Fig. 2.

The base A also extends in front of the body B, as represented in the photograph, and there is arranged above the front section of the base 35 the rectangular-shaped box or case G.

The fronts of the base A, box or ease G, and box or case F are covered by a plate, H, (shown in both photographs, but particularly in Fig. 1,) and which embraces the side columns or 40 sections, h, the front of which has the sunken section or recess h'. The plate also has the curved projection h² at the top, the door-frame h³, which is plain or unornamented, and the panels

h⁴ upon each side of the door h⁵, and the door h⁶. The stove or furnace also has the door h⁷, 45 which has a central sunken panel, h⁸, and a rounded border, h⁹, with line-work extending around it parallel with the edge. The door h⁵ has a plain rounded surface, h¹⁰, and also a line of bead-work, and the rounded projecting 50 section h¹¹, having a flat top, h¹². The door h⁶ has the general characteristics of the door h⁷. The door h¹⁴ has a plain border, h¹⁵, the bars h¹⁶, and the projection h¹⁷, the general shape of which is shown in the photographs. 55

We claim—

1. The herein-described design for a heating stove or furnace, the same comprising a base, A, the projection C, the body B, cylindrical in shape, the caps or boxes d e, the pipes D E, 60 and the boxing or casing F G, as illustrated and described.

2. In a design for heating stoves and furnaces, the base A, having the projecting section C, the cylindrical body B, the caps or 65 boxes d e, and the pipes D E, as shown and described.

3. In a design for stoves or furnaces, the plate H, having the sections or wings h, the long recesses or panels h', and the panels h⁴, 70 as illustrated and described.

4. In a design for a stove or furnace, the door h⁵, having the rounded surface h¹⁰, and the projection h¹¹, having the flat top h¹², as illustrated and described.

5. In a design for a stove or furnace, the base A, having the extension C upon the sides and back of less height than the base, and upon a line with the upper part thereof, as 75 illustrated and described.

FRANK A. MAGEE.
SYLVESTER VAN VORST.
